LOADING AND UNLOADING STATION FOR VERTICAL CONVEYER

Fredrick Theijsmeijer, Port Hope, Ontario, and Jack Hermans, Cobourg, Ontario, Canada, assignors to Rex Chainbelt Inc., Milwaukee, Wis., a corporation of Wisconsin

Filed Oct. 11, 1966, Ser. No. 4,233

Term of patent 14 years

(Cl. D55—1)

FIG. 1

FIG. 2

FIG. 3

FIG. 4

FIGURE 1 is a perspective view of a loading and unloading station for vertical conveyer embodying our new design;

FIGURE 2 is a front elevation view of the vertical conveyer station shown in FIGURE 1;

FIGURE 3 is a top plan view of the vertical conveyer station; and

FIGURE 4 is a side elevation view of the vertical conveyer station.

The dominant features of my design reside in the portions shown in full lines.

We claim:

The ornamental design for a loading and unloading station for vertical conveyer, substantially as shown and described.
